UNITED STATES PATENT OFFICE.

ABBIE L. PRESTON, OF OTTAWA, ILLINOIS.

NON-REFILLABLE BOTTLE.

1,182,034.

Specification of Letters Patent.

Patented May 9, 1916.

Application filed January 3, 1916. Serial No. 69,962.

To all whom it may concern:

Be it known that I, ABBIE L. PRESTON, a citizen of the United States, residing at Ottawa, in the county of La Salle and State 5 of Illinois, have invented a new and useful Non-Refillable Bottle, of which the following is a specification.

The present invention appertains to non-refillable bottles, and aims to provide novel 10 and improved means for closing the bottle and for preventing the same being refilled or reused without detection.

It is the object of the invention to provide novel means for holding a stopper in the 15 neck of a bottle whereby the stopper can only be removed by breaking or destroying a portion of the bottle which will prevent the refilling and reuse of the bottle in the original manner.

20 It is also within the scope of the invention to provide a non-refillable bottle which is comparatively simple and inexpensive in construction, as well as being practical and efficient in use.

25 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

30 The invention is illustrated in the accompanying drawing, wherein:—

Figure 1 is a vertical section through the neck of a bottle illustrating the improvements. Fig. 2 is a cross section on the line 40 2—2 of Fig. 1.

In the drawing, there is designated a bottle or other container 1 having a neck 2, which is provided with diametrically opposite outstanding alining tubular extensions 45 3 which are provided at their outer or remote ends with concaved integral closures or ends 4. These ends or closures 4 are relatively thin so as to be frangible, and the con-

caved sides are outermost so that the ends 4 will be protected against accidental injury. 50 The extensions 3 are quite firm, and are formed integral with the neck during the molding thereof, and are preferably located intermediate the ends of the neck.

A stopper 5 is adapted to fit snugly within 55 the neck 2 so as to extend past the extensions or socket members 3, and is provided adjacent its inner or lower end with a diametrical bore or opening 6 in which is fitted a coiled wire expansion spring 7 whose terminals are adapted to be projected into the extensions or keepers 3. The stopper 5 is preferably constructed of glass, the same as the bottle, so that the spring is exposed to view, although this is not mandatory. 65

In use, after the bottle is filled, a cork or equivalent stopper 8 is slipped into the neck beyond the extensions 3, to provide a tight closure for the bottle, and after the spring 7 is inserted in the opening 6 of the 70 stopper 5, the stopper is started into the neck, the spring being compressed so that it can move into the neck with the stopper 5. After the stopper is moved into place, as seen in Fig. 1, the spring 7 in expanding will 75 be projected into the extensions 3, and said extensions serve as keepers to hold the spring whereby the stopper 5 cannot be withdrawn unless the spring is released. To release and withdraw the spring, one of the 80 frangible ends or portions 4 is broken by any suitable implement, and this permits the spring to project out of the respective extension 3, whereby the spring can be withdrawn. This permits the stopper 5 to be 85 removed, and the cork stopper 8 can then also be removed. The contents of the bottle can be poured out, and the extension or nipple 3 which has been opened can be used for decanting the contents of the bottle if preferred.

90 Since one or both of the ends 4 are broken, the subsequent use of the bottle is prevented, that is, in the original manner. The present invention thus provides an effective means whereby a bottle after being 95 received by the consumer and opened, can-

not be refilled and reused without this fact being indicated by the injury to the bottle.

Having thus described the invention, what is claimed as new is:

A bottle neck having diametrically opposite outstanding tubular extensions provided with thin concaved frangible ends, a stopper insertible in said neck and having a diametrical opening, and a coiled wire expansion

spring to fit in said opening and expand into 10 said extensions when the stopper is inserted.

In testimony that I claim the foregoing as my own, I have hereto affixed my signature in the presence of two witnesses.

ABBIE L. PRESTON.
